[57] **ABSTRACT**

A transfer plasmid (factor K) is transferred from a first Pseudomonas organism to a second Pseudomonas organism. Factor K induces the mobilization of genes from the chromosome of the second Pseudomonas organism and under proper conditions will transfer the mobilized genes to a recipient organism in which those particular genes have been deleted. The factor K and the mobilized genes enter the recipient and become established there as stable separate plasmids constituting a plasmid aggregate. Non-transmissible artificial hydrocarbon degradative plasmids have been created in Pseudomonas organisms in this manner and (with factor K present in the host to accomplish the transfer) have been transmitted to other Pseudomonas recipients.

5 Claims, No Drawings

DISCRETE PLASMID CONSTRUCTION FROM CHROMOSOMAL GENES IN PSEUDOMONAS

BACKGROUND OF THE INVENTION

The terminology of microbial genetics is sufficiently complicated that certain definitions will be particularly useful in the understanding of this invention:

Plasmid — A hereditary unit that is physically separate from the chromosome of the cell; the terms "extrachromosomal element" and "plasmid" are synonymous; when physically separated from the chromosome, some plasmids can be transmitted at high frequency to other cells;

Transmissible plasmid — A plasmid that carries genetic determinants for its own intercell transfer via conjugation;

DNA — Deoxyribonucleic acid;

Bacteriophage — A particle composed of a piece of DNA encoded and contained within a protein head portion and having a tail and tail fibers composed of protein;

Deletion — The condition in which a substantial portion of the chromosomal DNA is missing;

Transducing phage — A bacteriophage that carries fragments of bacterial chromosomal DNA and transfers this DNA on subsequent infection of another bacterium;

Conjugation — The process by which a bacterium establishes cellular contact with another bacterium and the transfer of genetic material occurs;

Curing — The process by which plasmids can be selectively eliminated from the microorganism;

Curing agent — A chemical material or a physical treatment that enhances curing;

Degradative pathway — A sequence of enzymatic reactions (e.g. 5 to 10 enzymes are produced by the microbe) converting the primary substrate to some simple common metabolite, a normal food substance for microorganisms;

Replication — The process by which a piece of DNA divides itself into two identical copies;

Replicon — A genetic unit that enables a piece of DNA to undergo replication;

Auxotroph — A mutant organism that requires a food source containing a particular amino acid or vitamin for growth;

Recombinant — A cell in which a portion of a genetic fragment has been substituted in the chromosome;

(Sole carbon source) — Indicative of a mutant incapable of growing on the given sole carbon source;

(Plasmid)^{del} — Indicative of cells from which the designated plasmid has been completely driven out by curing or in which no portion of the plasmid ever existed;

(Plasmid)⁻ — Indicative of cells lacking in the designated plasmid or cells harboring a non-functional derivative of the given plasmid;

(Amino-acid)⁻ — Indicative of a strain that cannot manufacture the designated amino acid;

(Vitamin)⁻ — Indicative of a strain that cannot manufacture the designated vitamin and

(Plasmid)⁺ — Indicates that the cells contain the designated plasmid.

The symbol [OCT] as used herein signifies the plasmid aggregate composed of OCT, factor K and MER.

Plasmids are believed to consist of double-stranded DNA molecules. The genetic organization of a plasmid is believed to include at least one replication site and a maintenance site for attachment thereof to a structural component of the host cell. Generally, plasmids are not essential for cell viability.

Plasmids may be compatible (i.e. they can reside stably in the same host cell) or incompatible (i.e. they are unable to reside stably in a single cell). Among the 10 known plasmids, for example, are sex factor plasmids and drug-resistance plasmids.

As is shown in U.S. Pat. No. 3,813,316 - Chakrabarty the capability of some *Pseudomonas* species to degrade complex organic compounds is due to the presence of 15 one or more transmissible plasmids, each of which specifies the entire enzyme complement of a particular degradative pathway. Such plasmids are designated "degradative plasmids". As is described in the Chakrabarty patent unique *Pseudomonas* organisms have been developed by transferring a number of such degradative pathways to the same recipient. However, the application of this genetic engineering technique has, heretofore, been limited to the transfer of naturally-occurring degradative plasmids. However, a *Pseudomonas* organism may have a desired capability of degrading some given complex organic compound, but this capability is of chromosomal origin. If it be desired to transfer the desired capability to a recipient cell by the techniques described in the patent, these techniques 25 will not suffice.

It would be particularly advantageous to be able to transfer an entire enzyme complement of a particular degradative pathway, regardless of whether or not a naturally-occurring degradative plasmid is available therefor.

DESCRIPTION OF THE INVENTION

By the practice of the instant invention, once a *Pseudomonas* organism is found containing genes that specify the entire enzyme complement of a particular degradative pathway, if this pathway is not already plasmidborne, the requisite genes can now be transferred. This is accomplished by mobilizing these genes from the chromosome and transferring them to a preselected 40 recipient in which these particular genes have been deleted. The transferred genes then become established therein as a separate stable artificial degradative plasmid. Mobilization of genes for subsequent transfer in this manner is accomplished by utilizing a transfer plasmid (factor K).

MANNER AND PROCESS OF MAKING AND USING THE INVENTION

In brief, the process for transforming chromosomal genes that specify a particular degradative pathway into the form of an artificial non-transmissible plasmid is as follows:

1. select the primary substrate to be degraded;
2. identify a *Pseudomonas* organism capable of converting the primary substrate to some simple common metabolite;
3. determine whether the specifying genes are plasmid-borne or are chromosomal;
4. if the desired degradative pathway is specified by the chromosome, introduce factor K into the cell by selection techniques and
5. use the cell so modified genetically to transfer the genes for the degradative pathway to a recipient

Pseudomonas cell (factor K will, of course, also be transferred simultaneously), the recipient organism selected being one in which those particular genes have been deleted.

Recipient cells surviving growth on a minimal plate now contain the transmissible factor K and, separate therefrom (but constituting a plasmid aggregate therewith) the nontransmissible degradative pathway. Thereafter, the plasmid aggregate can be transferred to other recipient cells. Steps 1-5 can be repeated to introduce multiple compatible plasmids into the same recipient. Also this process can be used to introduce an artificial plasmid into a Pseudomonas cell which already has one or more plasmids so long as the ultimate plasmid content is compatible.

By the practice of this invention the development of cell capability in a single strain for the degradation and conversion of complex hydrocarbons can be extended for even greater efficiency to cope with massive oil spills or engage in the production of protein. Thus, for example, if a total of 10 degradative pathways are required for the efficient breakdown of a given crude oil, all that is necessary is that all the microorganisms providing these pathways be of the same strain in order to insure compatibility. The total complement of organisms all of the same strain may include a concentration of cells with four degradative plasmids and six concentrations of cells, each containing a different degradative pathway.

To facilitate the practice of this invention in the best mode contemplated, a culture of microorganisms possessing the transfer plasmid, factor K, is now on deposit with the United States Department of Agriculture. This culture is identified as follows:

P. putida PRS1 K⁺ (NRRL B-8043) — Derived from *Pseudomonas putida* PRS1 (ATCC No. 12633) by genetic transfer thereto of a transfer plasmid (factor K) from *Pseudomonas putida* strain PpG1 (ATCC No. 17453).

A sub-culture of this strain can be obtained from the permanent collection of the Northern Marketing and Nutrient Research Division, Agricultural Service, U.S. Department of Agriculture, Peoria, Ill., U.S.A.

Morphological observations in various media, growth in various media, general group characterization tests, utilization of sugars and optimum growth conditions for the strains from which the above-identified organisms were derived are set forth in "The Aerobic Pseudomonads: A Taxonomic Study" by Stanier, R. Y. et al. [Journal of General Microbiology 43, pp. 159-271 (1966)]. The taxonomic properties of the above-identified organisms remain the same as those of the parent strains. *P. putida* strain PpG1 (ATCC No. 17453) is the same as strain 77 in the Stanier et al. study.

All the organisms referred to herein are non-pathogenic as is the general case with laboratory strains of Pseudomonas.

The capability for creating plasmid structures from chromosomal genes has been made possible by two discoveries. First, was the discovery that there exists for the Pseudomonas species a transfer plasmid, factor K, serving as a gene transfer vector in somewhat the same way as the F plasmid, the sex factor in *E. coli*. Next, was the discovery that factor K could be used to mobilize chromosomal genes and transfer the mobilized genes to a recipient cell in which those particular genes have been deleted, the mobilized genes thereupon becoming

stabilized in the recipient as a separate inheritable plasmid.

Demonstration is given in the publication "Dissociation of a Degradative Plasmid Aggregate in Pseudomonas" by A. M. Chakrabarty (J. Bacteriol. 118 : 815-820, 1974) that the transfer of the [OCT] plasmid from *P. oleovorans* to *P. putida* strain PpG1 results in the acquisition by the recipient of three independent replicons: OCT (a non-transmissible plasmid specifying enzymes of the octane degradative pathway); MER (a transmissible plasmid, which confers resistance to high concentration of mercury ions) and factor K (the transfer plasmid). Factor K is shown as being responsible for the transfer of the OCT plasmid and some chromosomal genes. The chromosomal genes so substituted became part of the chromosome of the recipient cell (recombinant) as contrasted to the formation of a conjugant in the instant invention. In this invention, however, the recipient cell is deliberately selected as one in which the genes for the given degradative pathway have been deleted and as a result the transferred chromosomal genes cannot undergo recombination with the recipient chromosome. These genes, therefore, replicate as a separate artificial plasmid.

The compositions of the synthetic mineral media for growth of the cultures were the same for all the Pseudomonas species employed. The mineral medium was prepared from:

PA Concentrate:

100 ml. of 1 molar K₂HPO₄
50 ml. of 1 molar KH₂PO₄
160 ml. of 1 molar NH₄Cl

100 × Salts:

19.5 gm. MgSO₄
5.0 gm. MnSO₄·H₂O
5.0 gm. FeSO₄·7H₂O
0.3 gm. CaCl₂·2H₂O
1.0 gm. ascorbic acid
1 liter H₂O

Each of the above (PA Concentrate and 100 × Salts) was sterilized by autoclaving. Thereafter, one liter of the mineral medium was prepared as follows:

PA Concentrate — 77.5 ml.

100 × Salts — 10.0 ml.

Agar — 15.0 gm.

H₂O — to one liter (the pH is adjusted to 6.8 - 7.0).

All experiments were carried out at 32°C unless otherwise stated.

For experiments in the transfer of factor K a strain of *P. putida* PRS1 was selected. The biochemical and enzymological characterization of the several aromatic degradative pathways discussed herein and transductional genetic analyses thereof has been set forth in the literature [Ornston, L. N. 1971. Regulation of Catabolic Pathways in Pseudomonas. Bacteriol. Rev. 35 : 87-116]. The origin, derivation and phenotypes of *P. putida* strains and their mutants used in this work are set forth in Table 1.

This work (Table 2) has shown that factor K is indeed capable of mobilizing and transferring chromosomal genes from one strain of *Pseudomonas* to another strain and the resulting recombinants appear to be stable. About 50-80% of such recombinants acquire factor K, thus inheriting donorability of chromosomal genes to other suitable recipients making possible the transfer of factor K to different strains of *Pseudomonas*. The effort was made on two occasions to transfer chromosomal genes and thus factor K from *P. putida* strain PpG1 to *P. aeruginosa* strain PAO without success. However, this is believed not to be insurmountable and additional attempts will be made with restriction negative mutants of *P. aeruginosa* PAO.

The results of conjugational transfer of mandelate and quinate genes mediated by factor K are shown in Table 3.

some of Genes Specifying Dissimilatory Functions" — Leidigh et al. (J. Molec. Evolution 2 : 235-242, 1973). In Table 1 the phenotypes of known plasmids have been capitalized, while those of the chromosomal genes are designated in lower case letters.

The results of determining the ability of factor K to mobilize chromosomal genes is shown in Table 2 wherein auxotrophic mutants of *P. putida* PRS1 are used as recipients.

In carrying out the chromosomal genes transfer from strain PpG1 to a variety of strain PRS1 auxotrophic

60 Two *P. putida* PRS1 chromosomal recombinants are shown therein as genetic donors. It is known from the literature that the genes specifying enzymes involved in the degradation of D or L mandelate by *P. putida* PRS1 are totally absent in *P. putida* PpG1. Similarly, *P. putida* PpG1 lacks some genes which specify enzymes for quinate metabolism. All Mdl⁺ PpG1 conjugants obtained were Qui⁻ while all Qui⁺ conjugants obtained were Mdl⁻. Co-transfer of these two (mdl and qui) gene clusters has not as yet been observed.

Again equal volumes of overnight-grown donor (AC 116 and AC 117) cultures and the respective recipient organisms were mixed and kept in a stationary condition for 1 hour. Aliquots of 0.1 ml were then plated on glucose-minimal, mandelate-minimal and quinate-minimal plates with methionine supplementation, when required. The results suggest that PRS1 chromosomal mutations can be repaired at a high frequency and mdl and qui gene clusters can be transferred in finite numbers from strain PRS1 to strain PpG1.

Since *P. putida* PpG1 does not have any region of genetic homology corresponding to the mdl and qui genes, an investigation was made to determine whether these gene clusters were integrated at some site on the PpG1 chromosome or whether these genes would replicate as autonomously-replicating genetic fragments (plasmids). Table 4 sets forth the mandelate enzyme levels (specific activities in nanomoles of substrate consumed or product formed per minute per mg of protein) in certain conjugatants of PRS1, PpG1 and Mdl⁺PpG1 strains. An assay of the mandelate enzymes was made according to the method outlined in the article "Synthesis of the Enzymes of the Mandelate Pathway by *Pseudomonas putida*" (J. Bacteriol. 91 : 1140-1154, 1966).

The enzyme level designations in Table 4 suggest that the mandelate genes are expressed normally inside strain PpG1 (after transfer thereto of the mdl gene clusters from strain PRS1) and that the number of copies of such genes in both strains PRS1 (AC 78) and Mdl⁺PpG1 (AC 104) is presumably the same.

Curing degradative pathways from each strain with mitomycin C was accomplished by preparing several test tube of L broth [Lennox, E. S. (1955), Virology, 1, 190] containing varying concentrations of mitomycin C and inoculating these tubes with suitable dilutions of early stationary phase cells of the given strain to give concentrations 10^4 to 10^5 cells/ml. These tubes were incubated on a shaker at 32°C for 2-3 days. Aliquots from tubes that showed some growth were then diluted and plated on glucose minimal plates. After growth at 32°C for 24 hours, individual colonies were split and resotted on glucose-minimal and degradative pathway-minimal plates to give the proportion of MDL⁻ and QUI⁻ in order to determine the frequency of curing. It was, therefore, shown that in each instance the degradative pathway genes are plasmid-borne.

Several of the mandelate negative cured derivatives, when analyzed in the manner referred to above for the presence of mandelate enzymes, showed loss of all the mandelate enzymes, suggesting that curing leads to the loss of the entire gene clusters. This, in turn, indicates that these genes appear to replicate independently as plasmids.

Further proof for establishing the plasmid nature of mdl and qui gene clusters in *P. putida* PpG1 (to which these genes have been transferred from strain PRS1) is the high rate of transmissibility of such genes to other suitable recipients. The capability for transfer of chromosomal genes and MDL and QUI plasmids is shown in Table 6. The AC 104 organism, which was a Met⁻ mutant of strain PpG1 that had received the mandelate ge-

PRS1. However, both the mandelate and quinate genes in the PpG1 conjugatants (AC 104 and AC 107) can be cured at a very low frequency.

Several chromosomal recombinants (selection on glucose-minimal) acquired the mandelate plasmid (MDL) by secondary infection. Transfer of the MDL plasmid (selection on mandelate-minimal supplemented with

tryptophan) was often associated with the transfer of chromosomal genes. Similarly, AC 107, which had received the qui genes from strain PRS1, was able to transfer chromosomal genes as well as the QUI plasmid at a high frequency. Thus, transfer of mdl and qui genes from the K⁺PRS1 strain (AC 116, Table 3) to PpG1 recipient was accompanied by a simultaneous transfer of factor K to the respective recipient.

Autonomous replication of mdl and qui genes as plasmids in strain PpG1 was verified by transfer of such plasmids by transduction. Transducing phage, pf16, is known to be effective for the transfer of plasmids between organisms of strain PpG1 [Genetic Basis of the Biodegradation of Salicylate in Pseudomonas — Chakrabarty (J. Bacteriol. 112 : 815-823, 1972)]. Table 7 shows the results of transduational transfer of both MDL and QUI plasmids to PpG1 cells deleted for these genes. Transductants were selected on mandelate and quinate-minimal plates supplemented with required amino acids. Unlike conjugational transfer, there was no associated transfer of chromosomal genes during transduction of such plasmids. The transductants harbor the mdl or qui gene clusters as plasmids, since they can be cured as explained hereinabove from the transductants at low frequency. Unlike the conjugants, however, the MDL⁺ or the QUI⁺ transductants are incapable of transferring the MDL or QUI plasmids by conjugation to other recipients.

TABLE 7

Donor	Reci- pient	Select	Trans- duction Frequency	Trans- ductant Phenotype
AC 104	AC 2	MDL	3×10^{-7}	Trp ⁻ Mdl ⁺
	AC 10	MDL	1×10^{-6}	Met ⁻ Mdl ⁺
AC 107	AC 2	QUI	1×10^{-6}	Trp ⁻ Qui ⁺
	AC 10	QUI	8×10^{-7}	Met ⁻ Qui ⁺

Results set forth in Table 8 below indicate that *P. putida* PpG1 auxotrophic mutant AC 110, which is a QUI⁻ segregant of AC 107, still retains the donorability for chromosomal markers. This suggests that factor K was still present in the AC 110 organism, which had been cured of the QUI plasmid. However, AC 109, which had received the QUI plasmid from AC 107 by transduction, could not transfer either chromosomal genes or the QUI plasmid. Thus, QUI plasmid appeared to be non-transmissible, per se, and any transmission thereof, was because of the presence of factor K.

This conclusion is further supported by examination of the characteristics of a number of chromosomal recombinants using AC 107 as a donor. As noted in Table 6, 4-5% of chromosomal recombinants inherited the QUI plasmid under the conditions employed while nearly 50% of the chromosomal recombinants inherited the donorability. However, recombinants that acquire the QUI plasmid may or may not inherit factor K. AC 108, a recombinant, which had inherited QUI but not factor K was incapable (less than 1×10^{-8} transfer frequency) of transferring either chromosomal genes or the QUI plasmid to suitable recipients. However, if factor K were to be introduced into organism AC 108, this transfer plasmid would enable AC 108 to act as a donor for both QUI and other chromosomal genes. Thus, the presence of factor K is essential for the mobilization of QUI as well as the chromosome. Data for transmissibility of the MDL plasmid was the same as for QUI.

TABLE 8

Donor	Recipient	Marker Selected	Transfer Frequency
AC 107 (QUI ⁺ K ⁺)	AC 2	Trp ⁺	4×10^{-4}
AC 109 ^a (QUI ⁺ K ⁻)	AC 2	QUI ⁺	2×10^{-5}
AC 110 ^b (QUI ⁺ K ⁻)	AC 2	Trp ⁺	$< 1 \times 10^{-8}$

AC 108 ^c (QUI ⁺ K ⁻)	AC 10	Met ⁺	$< 1 \times 10^{-8}$
		QUI ⁺	$< 1 \times 10^{-8}$

^aAC 109 is a QUI⁺ transductant of AC 10 from AC 107 as donor. Out of 10 transductants tested none transferred either QUI or chromosomal markers.

^bAC 110 is a Mitomycin C-induced QUI⁻ segregant of AC 107.

^cAC 108 is a Trp⁻Ilv⁺ recombinant of AC 20 which has acquired QUI but not factor K (donor used with AC 107).

In Pseudomonas when factor K is utilized to mobilize chromosomal genes and transfer them to a recipient from which the chromosomal genes being transferred were deleted, the mobilized genes and factor K take the form of a plasmid aggregate. The presence of factor K assures transmissibility of the artificially created plasmids to other cells, although the frequency of transfer for such plasmids is usually 50-100 fold lower than that of most chromosomal genes, as would be expected.

In the best mode contemplated for the practice of this invention, therefore:

1. the primary substrate to be degraded is determined,
2. a Pseudomonas strain is identified and isolated that exhibits the capability for converting the primary substrate to some common metabolite (i.e. the organism exercises the requisite degradative pathway),
3. the strain of Pseudomonas (different from the organism in step 2) actually to be used to accomplish the substrate degradation is selected, this strain being one in which the genes specifying the requisite degradative pathway are missing,
4. the nature of the genes (in the organisms of step 2) specifying the requisite degradative pathway (e.g. plasmid-borne or chromosomal) is determined; this is accomplished by curing and conducting independent conjugal transmissibility tests (if the capability for the specific degradative pathway is transferred, the degradative pathway is plasmid-borne and transmissible in which case this invention is not needed; if the specific capability is not cured from the "donor" organism, factor K is employed by the exercise of the following steps:
  - a. prepare a multiple auxotrophic mutant in the strain harboring the degradative pathway to be transferred as described in the textbook, "Genetics of Bacteria and Their Viruses" by William Hays [John Wiley & Sons, Inc. (1965)];
  - b. introduce factor K into this strain by using an auxotrophic mutant of *P. putida* PRS1 K⁺ as donor and the multiple auxotroph as recipient; selection is made for the repair of any one of the requirements of the recipient auxotrophs (about 50% of the recombinants will have acquired factor K); this is followed by purification of 10-12 recombinants by single colony isolation and subsequent analysis for the presence of factor K;
  - c. transfer the desired degradative pathway to the Pseudomonas isolated in step 2 using the auxotrophic recombinant harboring factor K as the donor; transfer is by conjugation in the manner

11

described in the Chakrabarty patent (column 7, lines 10-38) and
 d. purify the conjugants; these conjugants contain the desired degradative pathway in the form of a plasmid that is non-transmissible in the absence of factor K.

Herein where reference is made to the quinic pathway it should be noted that this pathway applies for both quinic acid and p-hydroxybenzoic acid.

What we claim as new and desire to secure by Letters Patent of the U.S. is:

1. A process for transferring chromosomal genes specifying a hydrocarbon degradative pathway for a given substrate from a first strain of *Pseudomonas* and imparting said chromosomal genes as part of a plasmid aggregate into a second strain of *Pseudomonas* which does not contain said chromosomal genes comprising the steps of:

10

20

12

- a. introducing factor K, a transfer plasmid, into at least one organism of said first strain of *Pseudomonas* which mobilizes said chromosomal genes and forms a plasmid aggregate therewith,
  - b. admixing the resulting first strain of *Pseudomonas* with said second strain of *Pseudomonas* transferring said plasmid aggregate by conjugation,
  - c. placing the mixture on minimal plates containing said given substrate as the sole source of carbon and
  - d. purifying the resulting conjugants.
2. The process of claim 1 wherein the source of factor K is *P. putida* PRS1 K⁺.
3. The process of claim 1 wherein the hydrocarbon pathway is for quinic acid degradation.
4. The process of claim 1 wherein the hydrocarbon degradative pathway is for mandelate degradation.
5. The process of claim 1 wherein the first strain is *P. putida* PRS1 and the second strain is *P. putida* PpG1.
